UNITED STATES PATENT OFFICE.

STEPHEN M. QUINN, OF IOLA, KANSAS.

GAS-PRODUCER.

1,002,311.

Specification of Letters Patent. Patented Sept. 5, 1911.

Application filed August 12, 1910. Serial No. 576,839.

To all whom it may concern:

Be it known that J. STEPHEN M. QUINN, a subject of the King of Great Britain, residing at Iola, in the county of Allen and State 5 of Kansas, have invented certain new and useful Improvements in Gas-Producers, of which the following is a specification.

My invention relates to improvements in gas producers, the object of the invention 10 being to so design and construct a gas producer that coal will be maintained at a uniform depth on the grate thereof and be kept free from clinkers during coal combustion.

A further object of my invention is to 15 provide water cooling means for the grate of the gas producer, said grate to be revolvable and to be supplied with cooling water at intervals.

A further object of my invention is to 20 provide a gas producer which shall be simple of construction, inexpensive to manufacture, and efficient in operation.

Other objects will appear hereinafter.

With these objects in view my invention 25 consists in the novel construction and arrangement of parts as will be hereinafter fully described and more particularly pointed out in the appended claims.

My invention will be more readily understood by reference to the accompanying drawings forming a part of this specification, and in which,

Figure 1 is a side elevation of my improved gas producer, the concrete base or 30 foundation thereof being shown in section, Fig. 2 is substantially a vertical section, Fig. 3 is a top plan view of the rotary grate constituting a part of the gas producer, and Fig. 4 is a detail view showing a means for 35 rotating said grate.

The preferred form of my invention as illustrated in the accompanying drawings comprises a vertical cylindrical sheet metal body 1 having a lining of fire brick 2 and a 40 circular cover 3. The cylindrical body 1 is supported by bracket members 4, three of these members, as shown in Fig. 3, being the preferable construction. Centrally positioned in the cover 3 is coal chute 5 the lower 45 cylindrical portion of which extends downwardly into the body 1 and is arranged coaxially therewith. The upper portion of the coal chute 5 is enlarged into a spherical form, and resting thereon is a vertically disposed coal hopper 7, the feeding of coal 50 therefrom being governed by a valve 8

which is connected to an oscillatory lever 9 by means of a connecting rod 10, said lever being rigidly connected to the inner end of a shaft 11 journaled in the coal hopper. The outer end of the shaft 11 is squared, and rigidly connected thereto is an arm 12 carrying the adjustable weight 13 which serves to counterbalance the coal contained within the hopper 7. The lever 12 may be manually or otherwise operated when it is desired to open the valve 8 for feeding the coal to the grate below the chute 5. Connected to one side of the body 1 is a pipe 14 by means of which gas is conducted away from 70 the gas producer. Secured on the inner sides of the bracket members 4 are studs 15 upon which friction wheels 16 are mounted for carrying the rail 17, the latter being secured to the periphery of a shell 18 which is 75 arranged exteriorly to the body 1. An interior shell 19 is connected to the exterior shell 18 by means of an annular flange 18', this construction forming an annular water space between said shells. The lower edge 80 of the body 1 projects into said annular water space thus forming a seal. Formed integral with the interior shell 19 at the upper end thereof are a plurality of tubular radial arms 20 which are reinforced and 85 connected together by a series of arcuate ribs 21, the openings between said ribs and arms permitting gas to flow upwardly from the chamber inclosed within the interior shell 19 to the main chamber in the body 1. Centrally arranged at the juncture of the arms 20 is a conically formed recessed portion 22, and disposed below said recessed portion is a tubular passageway 23 which forms a communication between the tubular arms 20 and 90 the sealed space below the same.

The fire brick lining 2 of the body 1 is supported by an inwardly extending flange 24, as clearly shown in Fig. 2.

In order to introduce the necessary steam and air into the gas producer a pipe 25 is provided and connected with a source of steam and air supply, said pipe being rigidly secured in the concrete base or foundation 26 and leading into the sealed space inclosed 100 within the interior shell 19. A circular ash and water pit 27 arranged below the body 1 is provided in the concrete base 26, and extending into said pit are supports 28 on which the bracket members 4 rest. 105

29 indicates the water in the water pit 27 into which the shell 19 is submerged, thus

sealing the chamber contained therein. The inner end of the pipe 25 is tipped by a crown 30 which is provided with a semi-spherical deflecting surface 31 and ports 32, air and 5 gas passing through said ports as indicated by arrows in Fig. 2. In order to rotate the shell 19 a lever 33 is provided which is connected to a reciprocating rod 35 by means of a perforation 34; said rod 35 being connected to any source of power. The rod 33 is loosely connected to the rail 17 by means of a fork 36 formed therein, the legs of said fork embracing the head of the rail, as shown in detail in Fig. 4. In operation, 10 when the rod 35 is pulled in one direction the fork 36 automatically grips the rail 17 and causes the shell 19 to rotate. During the return movement of the rod 35 the spring 37 which is mounted on the lug 38 re- 15 turns the lever 33 to its normal position when the action is repeated as before.

In operation the annular space between the shells 18 and 19 into which extends the lower portion of the upper cylindrical body 25 1 and the ash pit 27 are filled with water, thus obviously effecting a water seal between said parts, and which prevents any of the valuable gases produced from escaping. The water in the annular space 30 naturally flows inwardly through the tubular arms 20 and some of it over the edge of the member 23 and thence down to the water in the ash pit below. In this way a constant water circulation is kept up which acts 35 as a water cooling means for the grate arms 20. The steam formed by the water passing through the intensely heated arms 20 is deposited with the steam from the steam supply pipe 25 into the chamber between the 40 ash pit water and the grate, whence it passes upwardly into the main chamber of the producer where it is mixed with the gases from the decomposed or distilled coal, and thus is utilized. When in use, the shell 19 is in- 45termittently rotated by means of the lever 33 so as to obviate the forming of large clinkers that otherwise would naturally form. This rotation also causes the ashes to fall to the ash pit and the coal to be kept 50 at a uniform level on the grate.

While I have shown what I deem to be

the preferable form of my device I do not wish to be limited thereto as there might be various changes made in the details of construction and arrangement of parts described without departing from the spirit of the invention comprehended within the scope of the appended claims.

Having described my invention what I claim as new and desire to secure by Letters Patent is:

1. A gas producer comprising an upright cylindrical body having a free lower edge, a rotary member provided with a water seal arranged to receive said lower edge, 6 hollow grate arms in said member in open communication with said water seal and provided with a central discharge opening, and means for rotating said member, substantially as described. 70

2. A gas producer comprising an upright cylindrical body having a free lower edge, a rotary member provided with a water seal arranged to receive said lower edge, radially disposed substantially horizontal hollow 75 grate arms in said member and having their outer ends in open communication with said water seal, a common chamber at the center of said arms and in open communication therewith, and an open tubular member projecting upwardly into said common chamber, substantially as described. 80

3. A gas producer comprising an upright cylindrical body having a free lower edge, a rotary member provided with a water seal 85 arranged to receive said lower edge, radially disposed substantially horizontal hollow grate arms in said member and having their outer ends in open communication with said water seal; a common chamber at the center 90 of said arms and in open communication therewith, said chamber having an upwardly recessed top, and an open tubular member projecting upwardly into said common chamber, substantially as described. 95

In testimony whereof I have signed my name to this specification in the presence of two subscribing witnesses.

STEPHEN M. QUINN.
